UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed March 8, 1921. Serial No. 450,748.

To all whom it may concern:

Be it known that I, FRED S. CARR, a citizen of the United States, and a resident of Newton, in the county of Middlesex and 5 Commonwealth of Massachusetts, have invented an Improvement in Fasteners, of which the following description, in connection with the accompanying drawings, is a specification, like characters on the drawings 10 representing like parts.

This invention pertains to improvements in fasteners. It is among the objects of the invention to provide a socket for separable fasteners in which, where relatively light 15 gauge metal is used for the socket casing, the strength of the socket is materially increased, and in which smoothness of operation of the fastener is promoted.

In the drawings, which show a preferred 20 embodiment of my invention:—

Figure 1 shows two pieces of fabric held together by a stud and socket fastener;

Fig. 2 is a section on the line 2—2 of 25 Fig. 1, being partly in elevation;

Fig. 3 is a front elevation of a preferred 30 form of socket;

Fig. 4 is a front elevation of a stud; and

Fig. 5 is a section on the line 5—5 of Fig. 3, being partly in elevation.

Referring to the drawings and to the preferred form of my invention selected for 35 illustrative purposes, I have shown a stud which may be of the usual form including a head 6, a neck 7 and base 8 attached to the stud-carrying fabric 9 in any suitable way as by stitching through the stitch-receiving apertures 10. The preferred form of socket illustrated is of the type adapted to be sewn to the carrying fabric, though types of socket 40 adapted to be metallically secured to their carrying fabrics may to advantage utilize certain features of my invention. The socket illustrated includes a casing 11, having a stud-receiving aperture 12 containing a 45 spring 13 which may be of any suitable form providing one or more resilient jaws intersecting the stud-receiving aperture. The metal around the stud-receiving aperture 12 is preferably beaded, being turned back on

itself, as best shown in Fig. 5 to provide a 50 bead 14 surrounding the marginal portion of the stud-receiving aperture. This aperture greatly increases the strength of the socket casing for any given grade of metal used in its construction, and, whether or not the 55 metal used for the socket is of such gauge as to require reinforcement, the bead is preferably provided because it increases the smoothness of operation of the fastener when stud and socket are engaged and disengaged, particularly when under lateral 60 strain. This smoothness of operation is provided not only because the thickness of the socket adjacent the portion thereof which bears on the stud when under lateral strain 65 is increased, but because a smooth edge is provided, preferably rounded as illustrated, so that there is no tendency for the inner edge of the socket surrounding the stud-receiving aperture 12 to dig into the neck of 70 the stud and unduly increase frictional resistance to desired separation of stud and socket when under lateral strain. While the bead 14 is preferably provided by turning the edge of the metal inwardly and backwardly so that the projecting bead is on the 75 inside of the casing, the bead may be formed in other ways while retaining many of the advantages produced by the construction illustrated.

Claims.

1. A socket for separable fasteners including a casing having a plate with a stud-receiving aperture therethrough, said plate having a return flange at its edge adjacent 85 the aperture.

2. The method of strengthening the socket plate of a separable fastener which comprises beading the plate at its edge surrounding the stud-receiving aperture therein. 90

3. The method of strengthening the socket plate of a separable fastener which comprises punching the stud-receiving aperture therein providing a tubular flange and expanding said flange outwardly to provide a 95 bead doubling the thicknesses of metal adjacent the aperture.

4. A socket for separable fasteners includ-

ing a casing having a plate with a stud-receiving aperture therethrough, said plate being beaded at its edge adjacent the stud-receiving aperture.

5. A socket for separable fasteners including a casing having a plate with a stud-receiving aperture therethrough, said plate be-

ing beaded at its edge adjacent the stud-receiving aperture, the bead projecting toward the inside face of the plate.

10 In testimony whereof, I have signed my name to this specification.

FRED S. CARR.
